UNITED STATES PATENT OFFICE

2,488,655

PAINT APPLICATOR

Ona A. Bennett, Louisville, Ky.

Application October 1, 1947, Serial No. 777,242

13 Claims. (Cl. 91—62.5)

1

This invention relates to new and useful improvements in paint applicators and the primary object of the present invention is to provide a roller including means operatively connecting the latter to a source of fluid to regulate a flow of fluid to the roller so that the latter may be used to paint surfaces without the necessity of placing the latter into a paint container.

Another important object of the present invention is to provide a paint applicator embodying novel and improved valve means for controlling a flow of fluid from a source to the roller mechanism.

A still further object of the present invention is to provide a paint applicator including a feed chamber so designed as to permit the same to be quickly and readily emptied or cleaned.

A still further aim of the present invention is to provide a paint applicator that is simple and practical in construction, strong and efficient in use, neat and attractive in appearance, relatively inexpensive to manufacture, and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is bottom plan view of the present paint applicator;

Figure 2 is a side elevational view of Figure 1, and with parts broken away and shown in section;

Figure 3 is an enlarged longitudinal vertical sectional view taken substantially on the plane of section line 3—3 of Figure 1, and with parts of the fluid conduit broken away and shown in section;

Figure 4 is a transverse vertical sectional view taken substantially on the plane of section line 4—4 of Figure 2, and with parts thereof broken away and shown in section;

Figure 5 is a transverse vertical sectional view taken substantially on the plane of section line 5—5 of Figure 2, and with parts broken away and shown in section;

Figure 6 is a transverse vertical sectional view taken substantially on the plane of section line 6—6 of Figure 2;

Figure 7 is a fragmentary longitudinal vertical sectional view showing the valve means for the feed chamber in slightly modified form; and,

Figure 8 is a fragmentary side elevational view of Figure 7.

2

Referring now to the drawings in detail, and more particularly to Figures 1—6 inclusive, wherein there is disclosed a preferred embodiment of the present invention, the numeral 10 represents a shank provided with a substantially U-shaped integral extension 12 at one end. Journalled on the free end of this extension is a roller 14 comprising a cylindrical core 16 and an absorbent sleeve 18 secured to the outer periphery of the core. At the opposite end of the shank is provided a handle 20.

Adjustably embracing a portion of the roller 14, is an arcuate transverse shield 22 having end flanges 24. This shield is provided with a transverse aperture 26 that communicates with an aperture 28 in a casing 30 and further communicates with the outlet opening 32 in a hollow feed chamber 34. It is preferred, that the shield, casing and feed chamber be integrally formed. However, the elements may be separate parts suitably secured to each other without deviating from the scope of the present invention.

Fixedly secured to substantially the center of chamber 34, is one end of a substantially cylindrical valve housing 36 that communicates with one end of an angular feed tube or fluid conduit 38.

Receivably engaging the free open end of the housing 36, is a packing gland 40 in which is slidably mounted a needle valve 42. The inner end 44 of the valve 42 is preferably pointed to engage a conical bore or seat 46 provided in the fixed end of the housing communicating with chamber 34.

Pivotedly mounted as at 48 on the conduit 38 is 35 the bifurcated end 49 of a lever or trigger 50. This lever is removably secured adjacent its free end to valve 42. The outer free end of the lever is disposed at a convenient location relative to the handle 20. A transverse recess 52 is provided

40 in the upper portion of casing 30 and receives a transverse bar 54 substantially trapezoidal in cross-section, that is pivotally mounted on pins 56 carried by the casing. This bar 54 constitutes a valve for controlling opening 26 in the shield.

45 Spring arms 58 carried by the casing 30 bear upon the outer face of bar 54 to normally retain the same in a positon for closing opening 26.

In practical use of the device, the conduit 38 is coupled to the outlet line 60 leading from a 50 source of fluid such as a paint pressure tank or the like (not shown). When the lever 50 is pulled by a finger toward the handle 20, the pointed end of the needle valve is disengaged from its normal tight fitted position in seat 46 to permit a 55 flow of fluid into chamber 34. As the pressure of

the fluid increases in chamber 34, the fluid will be forced against the inclined face of bar 54 rotating the bar slightly to permit the fluid to pass through openings 28 and 26 to engage the absorbent sleeve 18 of the roller. When lever 58 is released, spring 62 embracing the needle valve and biased between the packing gland 48 and a retaining ring 64 mounted on the needle valve, will carry the pointed end 44 of the needle valve again into seat 46, preventing a flow of fluid into the chamber 34.

It should be noted, that the housing 36 and the conduit 38 are retained or supported in position to the shank 10 by use of pairs of arms 66 removably secured to each other and having their arcuate terminal portions 68 formed to embrace the periphery of the shank, the conduit and the valve housing. These arms may be adjusted for positioning of the shield relative to roller 14.

For the purpose of removing any fluid remaining in the chamber 34 and for cleaning the inner surface of the chamber 34, there are provided nipples 70 at each end of the chamber that receivably engage closure cap 72.

Reference is now directed to Figures 7 and 8, wherein there is disclosed a valve means for controlling opening 26 in the shield 22 in slightly modified form. In this embodiment, a transverse groove or channel 74 is provided in the inner periphery of the casing 30 and engages the enlarged edge or beading 76 of a plate 78 constituting a valve within the opening 28 of the casing for regulating opening 26 in the shield. The ends of the plate 78 are pivoted to the ends of the casing by a pin or the like 80 on which is fixedly secured one end of a link 82. The free end of the link 82 is connected to a coil spring 84 carried by the outer face of chamber 34 to normally retain the plate in a closed position relative to opening 26. This plate is so designed as to be actuated or pivoted forwardly as the fluid passes from the chamber to contact the same. However, the plate will not allow fluid to pass from the shield into the chamber.

In view of the foregoing description taken in conjunction with the accompanying drawings it is believed that a clear understanding of the construction, operation and advantages of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claims.

Having described the invention what is claimed as new is:

1. A paint applicator comprising a shank, a roller journaled on said shank, a feed chamber detachably secured to the shank adjacent the roller and having an outlet opening, a shield carried by said chamber having an aperture communicating with the outlet opening, a first valve disposed adjacent the shield and said feed chamber controlling the flow of fluid through the outlet opening, a valve housing carried by said feed chamber and having a delivery passage communicating with said feed chamber, a fluid conduit between said housing and a source of fluid, a further valve mounted in said housing for controlling a flow of fluid through the delivery passage to said chamber, means for actuating said further valve, and means for supporting said shank

relative to said conduit, said shield being concavo-convex and having end flanges, said shield constituting a trough and receiving said roller.

2. The combination of claim 1 wherein said first valve includes a pivotal member normally closing said outlet opening.

3. The combination of claim 1 wherein said first valve includes a pivotal member and spring means normally retaining said member in a closed position relative to said outlet opening.

4. The combination of claim 3 wherein said pivotal member is actuated to open said outlet as a fluid flows from the chamber into the aperture provided in said shield.

15 5. The combination of claim 1 wherein said supporting means includes removable brackets carried by said shank and connected to said conduit.

20 6. The combination of claim 1 wherein said further valve includes a needle valve slidably mounted in said housing, and said actuating means for said further valve including a lever pivotally mounted on said conduit and connected to said needle valve.

25 7. A paint applicator comprising a shank, a roller journaled for rotation on said shank, said shank terminating in a handle portion, an arcuate shield having end plates, said shield constituting a trough and receiving said roller, a casing carried by said shield and having an opening, means securing the casing to the shank, said shield having a slot therein proximate the roller and communicating with the interior of said casing, a dispensing chamber carried by said casing, a valve housing communicating with said chamber and including a supply passage, a supply pipe for introducing fluid into said valve housing, a valve controlling the flow of fluid through said supply passage, means carried by said supply pipe for operating said valve, and a further valve mounted in the opening in said casing and controlling the fluid passing from said chamber and through the slot in said shield.

30 8. A paint applicator comprising a shank, a roller journaled for rotation on said shank, said shank terminating in a handle portion, an arcuate shield having end plates and constituting a trough receiving said roller, a casing carried by said shield and having an opening, said shield having a slot therein proximate the roller and communicating with the interior of said casing, a dispensing chamber carried by said casing, a valve housing communicating with said chamber and having a supply passage, a supply pipe for introducing fluid into said valve housing, a valve controlling the supply passage in said dispensing chamber, means carried by said supply pipe for operating said valve, an elongated valve member pivoted to the casing and received in the opening in the casing, said valve member controlling the passage of fluid from said chamber, said valve member being actuated to an open position by fluid in said chamber, and means yieldingly urging said valve member to a normally closed position.

35 9. The combination of claim 8 wherein said valve includes an elongated body portion spaced relative to said supply pipe, said means for operating said valve including a lever pivoted on said supply pipe and engaging the body portion of said valve.

40 10. A paint applicator comprising a shank, a roller journaled for rotation on said shank, an elongated arcuate shield partially embracing the roller and having a longitudinal slot therein

through which a fluid is adapted to pass to contact the roller, a casing carried by said shield and having an opening therein, means securing the casing to the shank, said casing communicating with said slot, a feed chamber communicating with said casing, means for supplying fluid to said feed chamber, an elongated valve member positioned in the opening in said casing for controlling the passage of fluid from the slot in said shield, pivot pins at the ends of said valve member and mounted on said casing, and spring means normally urging the valve member to a closed position, said valve member being responsive to pressure within said feed chamber for actuation to an open position.

11. The combination of claim 10 wherein said valve member includes an inclined longitudinal face forming a contact surface for liquid in said feed chamber.

12. In a paint applicator including a roller and support means for the roller; a liquid dispenser comprising an arcuate shield having end plates, said shield constituting a trough and receiving the

roller, said shield having a longitudinal opening therein proximate the roller, a dispensing chamber for supplying liquid through the opening in said shield to the roller, means for introducing liquid into said chamber, and a valve normally closing the opening in said shield, said valve being responsive to a predetermined pressure in said chamber for opening movement.

13. The combination of claim 12 wherein said valve includes a pivotal bar having a sloping longitudinal face forming a contact surface for liquid in said chamber.

ONA A. BENNETT.
